[57]

ABSTRACT

An adjustable gage for sewing machines comprising a base member and a gage of inverted U-cross-section, slideable on the base member. The base member is provided with a spring secured to the base member and engageable between a pair of a row of teeth provided on the underside of the gage, to permit an adjustment of the gage in a desired position relative to a fabric. A magnetized block is slidably mounted between the forward ends of the gage member and is displaceable vertically to engage by magnetic attraction the feeder plate or table surface of the sewing machine.

ADJUSTABLE GAGE FOR SEWING MACHINES

BACKGROUND OF THE INVENTION.

The present invention relates to gages for sewing machines in general, and in particular to an adjustable gage for a sewing machine for setting the distance of a seam relative to the edge of a fabric to be sewn.

An important object of the invention is to provide a gage of the above character comprising a base member securable to a sewing machine table and a slidable gage member thereon the guide surface whereof may be adjusted to space a seam at a desired distance from the edge of a fabric to be sewn.

Another object of the invention is to provide a gage provided with a magnetized block which is displaceable upwardly and downwardly on an elevated feeder plate on the table proper of a sewing machine and which will be held firmly on either the feeder plate or on the table.

A further object of the invention is to provide an attachment for existing adjustable gages, which comprises a magnetized block of the above character displaceable upwardly and downwardly for adhering to a feeder plate or table of a sewing machine.

Still another object of the invention is to provide devices of the above character which are simple in construction and operation.

These and other objects of the invention will be apparent from the following description and the accompanying drawing in which,

FIG. 1 is a perspective view of the gage and part of a sewing machine with a fold of fabric to be stitched;

FIG. 2 is a side elevational view of the guid with the table and feeder plate shown in cross-section;

FIG. 3 is a section taken on line 3—3 of FIG. 1;

FIG. 4 is a front view of the guide;

FIG. 5 illustrates variations of pins used for securing the gage to a sewing machine table;

FIG. 6 illustrates a modification adapted for use with existing gages and

FIG. 7 shows another variation of a securing pin.

Referring now to the drawing in detail, the gage comprises a top member 8 slidable on a base member 10. The base member 10 is provided with a pair of slotted steel locating pins 22, screwed into the base member, by means of which pins the base member is snugly secured to the sewing machine table 32. The base member 10 is thus held firmly in the table 32 and is prevented from longitudinal lateral and vertical displacement on the machine table. The holding pins may also be exchangeable. Instead of steel pins 22, resilient plastic pins 26 (FIG. 5) formed with circular ridges 27 may be used or plastic pins 40 (FIG. 7) formed with spuds 40 may be used for the same purpose.

Normally sewing machine tables 32 are provided with a pair of holes for the insertion of the holding pins. Some sewing machine tables, however, are provided with more than a pair of holding pin receiving holes, in which case the base member 10 may be provided with multiple pins corresponding in number to the number of holes in the table.

The base member 10 may be made of magnetized ferrous material, as shown in FIG. 3 so that it will adhere to the machine's steel table 32, thus adding to its holding strength on the table against vertical displacement.

The base member 10 may, likewise be made of a plastic material (not shown).

Slidably mounted on base member 10 is a generally U-shaped gage member 8 formed with a tongue 42 guided in groove 44 of base member 10. The bottom edges of sides 46 of the gage member are formed with a plurality of teeth 34 and interspaces 35 which are adapted to receive the transverse portion 37 of a U-shaped spring 14 the ends 39 of which are fixedly secured to the base member by screws 41. The spring 14 thus biases upwardly with its transverse portion 37 the rear end portion of gage 8, thus causing the forward end portions 43 downward towards the feeder plate 28 of the sewing machine.

The end portions 43 are formed with vertical longitudinal slots 18 in which are received extensions 16 of a magnetized block 12 freely slidable between the end portions 43. The magnetized block 12 is thus attracted in intimate engagement with the feeder plate 28 of the sewing machine and front face 46 acts as a guide for the edge 30 of a fabric 31 held down by the foot 36 and being stitched by the needle 38 along a seam as shown in dotted lines in FIG. 1.

When it is desired to form a wider seam relative to the edge 30 of the fabric 31, the transverse portion 37 of the spring 14 is pressed down, thus disengaging it from teeth 34. The gage member 8 is slid a desired distance in the direction of the arrow (FIG. 2) and the transverse end 37 is engaged between another pair of teeth 34.

It will be noted that the method of slidably mounting the magnetized block 12 in the forward end portions 43 of the gage permits this block to adhere to the surface of the table 32 proper instead of the feeder plate 28 when the gage is moved to its furthermost position 35 in the direction of the arrow of FIG. 2. This may be desirable when a seam considerably wider than that shown in FIG. 1 is desired.

The principle underlying the use of a displaceable magnetized gage block may be applied to use with existing gages. As shown in FIG. 6, a magnetized gage block is similarly slidably mounted in a clamp 50 which is clamped on a gage plate 52 of an existing gage 54 shown in dotted lines.

I claim:

1. An adjustable gage assembly comprising a base member having top, bottom and side walls, means for securing said bottom wall to a table of a sewing machine, a gage member slidable on said base member for controlling the distance of a running stitch relative to the edge of a material, means for adjustably securing said gage member on said base member at a predetermined lateral distance from a needle of a sewing machine, said base member being formed with a longitudinal guide groove, said gage member being of inverted U-cross-section having a longitudinal tongue portion engaging with said groove, said gage member having downwardly extending sides, the bottom edges of said sides being formed with a plurality of teeth, an upwardly inclined U-shaped spring secured with its ends to the side walls of said base member, said U-shaped spring having a transverse top portion engageable between an adjacent pair of said teeth for securing the gage member in a desired position relative to said base member.
2. An adjustable gage assembly as set forth in claim 1, wherein said sides have forward portions provided with vertical longitudinal slots, a magnetized block

disposed between said forward portions having lateral extensions slidable in said slots.

3. An adjustable gage assembly according to claim 1, wherein said means for securing said base to a sewing machine table are a plurality of plastic pins adapted to be screwed to said bottom wall of said base member, said plastic pins being formed with spaced circular ridges.

4. An adjustable gage as set forth in claim 1, wherein said means for securing said base to a sewing machine table are a plurality of plastic pins adapted to be screwed in said bottom wall of said base member, said plastic pins formed with circumferentially arranged spuds.
